UNITED STATES PATENT OFFICE.

NEAL BAILEY, OF TULSA, OKLAHOMA.

KEY HOLDER.

Application filed May 6, 1927. Serial No. 189,215.

This invention relates to a key holder adapted to be secured to a belt or other article of wearing apparel. One of the objects of the invention is to produce a simple, neat and attractive key holder adapted to be secured and held on the wearing apparel. A further object is to produce a device of this kind having its elements so arranged that any selected key can be easily removed without removing any of the other keys.

With the foregoing and other objects in view the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. 1 is a perspective view of a key holder embodying the features of this invention.

Fig. 2 is a perspective view on a smaller scale, showing a portion of a belt equipped with the key holder, the front of the belt being exposed.

Fig. 3 is a view similar to Fig. 2, showing the rear of the belt.

To illustrate one form of the invention, I have shown a key holder made of a single piece of wire bent to form a belt-receiving member and a key-receiving loop. The wire is bent, or folded on itself, at a point midway between its ends, as shown at A. The belt receiving member is preferably a loop comprising a hook 1 beginning at the bend A. At this point, the wire members are located adjacent to and parallel with each other, so as to form a double wire strand. The two wire members extend upwardly from the hook 1, as shown at 2, and then downwardly as shown at 3, to form opposite sides of the belt-receiving loop, the top of said loop being formed by the bend 4. These wire members have separated portions forming an eye 5 in which the end of the hook 1 is located, said wire members being twisted together above and below the eye, as shown at 6 and 7.

The key-receiving loop comprises bottom members 8 extending in opposite directions from the twisted portions 7 below the eye 5, and side members 9 extending upwardly from the outer ends of said bottom members, said side members 9 being provided with

hook-shaped overlapping ends 10 forming the top of the key-receiving loop.

The end members 10 yieldingly engage each other, and they can be separated from each other to receive and to release the keys.

The belt B extends through the loop formed by the wire members 1, 2, 3, 4, 5 and 6. The key-receiving loop is exposed at the front of the belt, as shown in Fig. 2, and the separable ends of this loop are preferably higher than the top of the belt, while the bottom of said loop lies below the belt to provide an unobstructed key-receiving space beyond the belt, the keys being supported on the bottom members 8, as suggested by dotted lines in Fig. 2. The key-receiving loop surrounds the belt-receiving loop, and when the free ends 10 are separated from each other a key can be applied to either of the side members 9 which lie at opposite sides of the belt-receiving loop.

When the device is in service, any one of the keys hanging from the bottom members 8 can be removed without removing any of the other keys. This is due to the fact that all of the keys can be moved across the top of the loop so as to pass from one side member 9 to the other, in such a manner that the user can select any key and withdraw it at the separable ends 10.

I claim:

1. In a key holder, a belt-receiving member, and a key-receiving loop surrounding said belt-receiving member, said key-receiving loop comprising side members, made of wire, located at opposite sides of said belt-receiving member and provided with hook-shaped upper ends yieldingly engaging each other and separable from each other to permit a selective release of the keys from each of said side members.

2. In a key holder, a belt-receiving loop, and a key-receiving loop surrounding the first mentioned loop, said key-receiving loop having bottom members below the belt-receiving loop and free end members separable to receive the keys, said end members being adjacent to the top of the key-receiving loop.

3. In a key holder made of a single piece of wire, a belt-receiving loop, and a key-receiving loop surrounding the first mentioned loop, the wire being doubled on itself to provide a pair of companion wire members located adjacent to each other in the belt-receiving loop and diverging therefrom to form the key-receiving loop, the ends of the

wire being separable from each other to receive the keys.

4. In a key holder made of a single piece of wire, a belt-receiving loop, and a key-receiving loop surrounding the first mentioned loop, said belt-receiving loop including two wire members located adjacent to each other and provided with a hook-shaped portion and an eye in which the end of said portion is located; said key-receiving loop including a pair of hook-shaped members having overlapping ends yieldingly engaging each other and separable from each other to receive the keys.
5. In a key holder made of a single piece of wire, a belt-receiving loop comprising a hook formed by two wire members located adjacent to and parallel with each other,

said wire members being extended from the hook to form the belt receiving loop and provided with separated portions forming an eye in which the end of said hook is located, said wire members being twisted together at opposite sides of the eye; and a key-receiving loop comprising bottom members extended in opposite directions from the twisted portions below said eye, and side members extending upwardly from the outer ends of said bottom members, said side members being provided with hook-shaped overlapping ends yieldingly engaging each other and separable from each other to receive the keys.

In testimony that I claim the foregoing I hereunto affix my signature.

NEAL BAILEY.
